DESIGN FOR A LIGHTING FIXTURE

William E. Vogel, Los Angeles, Calif.

Application November 9, 1939, Serial No. 88,141

Term of patent 3½ years

To all whom it may concern:

Be it known that I, William E. Vogel, a citizen of the United States, residing in the city of Los Angeles, county of Los Angeles, and State of California, have invented a new, original, and ornamental Design for a Lighting Fixture, of which the following is a specification, reference being had to the accompanying drawing, forming a part thereof.

Fig. 1 is a perspective view of a lighting fixture showing my new design; and

Fig. 2 is a side elevational view thereof.

I claim:

The ornamental design for a lighting fixture, as shown.

WILLIAM E. VOGEL.
